TOY CLOCK

Hymie D. Berman, Minneapolis, Minn.

Application February 5, 1951, Serial No. 14,106

Term of patent 14 years

(Cl. D34—15)

To all whom it may concern:

Be it known that I, Hymie D. Berman, a citizen of the United States, residing at Minneapolis, Hennepin County, Minnesota, have invented a new, original, and ornamental Design for Toy Clock, of which the following is a specification, reference being had to the accompanying drawing, forming a part hereof.

Fig. 1 is a front elevational view of a toy clock, showing my new design;

Fig. 2 is a side elevational view of the same; and

Fig. 3 is a rear elevational view of the toy clock shown in Fig. 1.

The side of the toy clock not shown is substantially the same in appearance as the side shown.

I claim:

The ornamental design for a toy clock, substantially as shown and described.

HYMIE D. BERMAN.
